MECHANICAL INDICATING CURRENT LIMITER

Michael D. Lazar, New York, N. Y., assignor to
Burndy Engineering Company, Inc., a corpora-
tion of New York

Application November 14, 1952, Serial No. 320,453

9 Claims. (Cl. 200—121)

1

My invention relates to current limiters and more particularly to the indicating variety.

Previous efforts have been largely confined to the peep-hole type through the window of which the parted fusible wire of the blown limiter could be detected. Such construction was not satisfactory in many circumstances.

In most installations, the limiters are installed side by side in a box. The box itself is usually mounted with other equipment. These crowded conditions, plus the fact that there is usually poor lighting in the area, make it very difficult to detect a blown limiter. In addition, detecting a blown limiter becomes immeasurably more difficult if the limiter happens to have been blown by a relatively low current flowing for a long time. These conditions will cause a very small section of the fusible wire to melt without the discoloring explosion or arcing which would make for easier detection.

Another phase of the problem is the need for completely covering the fusible wire and filling the limiter chamber with rockwool, quartz, or some such suitable material. This is to quench the arc and suppress the usual explosion, which occurs when the limiter blows under very high current. The suppressing material, however, interferes with visual indication of the fuse condition.

Accordingly, the principal object of my invention is to provide an explosion-proof limiter which is not dependent upon peep-holes, or discoloration for indicating its condition.

Other objects are to provide such a limiter that is light weight and suitable for aircraft where excess weight means a diminished fuel capacity; to provide a limiter which will possess the same operating characteristics at elevations of 50,000 feet as it does at sea level; to provide a limiter with operating characteristics that will permit a controlled heat dissipation to allow certain overloading faults to be cleared; to provide a limiter that will permit its condition to be indicated by touch to permit ready detection in dark areas; to provide an indicating limiter the fuse of which can be imbedded in a suppression material; and to provide an indicating limiter having the foregoing characteristics which is small, of sturdy construction, relatively inexpensive and capable of being mass produced.

I accomplish these and other objects and obtain my new results as will be apparent from the device described in the following specification, particularly pointed out in the claims, and illustrated in the accompanying drawing, in which:

Fig. 1 is a front elevation of the indicating

2

limiter with one end partially removed to show a corner of its construction.

Fig. 2 is a plan view of one half of the housing with fuse and indicator sub-assemblies in their respective positions and indicator projected.

Fig. 3 is a transverse sectional view of the complete limiter taken in the plane 3—3 of Fig. 2.

Fig. 4 is a fragmentary cross section of the housing adjacent the indicator illustrating a modification thereof.

I accomplish the various objects of my invention by providing a limiter 10 having a plunger 11 which is externally projected, as shown in Fig. 1, when the limiter is blown. Thus the condition of the limiter can be detected both visually and by touch.

The operating mechanism is contained in a housing comprising two halves 12 and 12a made of insulating and fire-resisting material molded into the desired shape.

The housing half 12 is provided with a fuse chamber 13 and an indicator containing chamber 14 for housing the fuse assembly 15 and the indicator assembly 16, respectively.

The fuse assembly 15 comprises two blades preferably U-shaped pieces of sheet metal 17 and 18, each folded over an end of the fuse wire 19.

The indicator assembly 16 comprises two metal contacts 20 and 21 preferably made of folded over pieces of sheet material to each of which

is attached one end of a wire 22 made of high resistance metal such as Nichrome. The Nichrome wire 22 is of sufficient length and strength to hold a coiled spring 23 compressed intermediate two insulating washers 23a positioned

adjacent to the two contacts 20 and 21. The plunger 11 forming the indicator extends through the coiled spring 23 and abuts the contact 21 at one end while the other end is securely fastened to the contact 20. Thus the Nichrome

wire 22, extending alongside the plunger and secured at one end to the plunger and contact 20, and to the other end by contact 21, if made discontinuous as shown in Fig. 2, permits the coiled spring 23 to drive the plunger and connected contact away from the remaining contact. The two contacts are prevented from escaping from the indicating chamber by the housing barrier 24 and its corresponding barrier 24a in the half 12a. The plunger 11 is positioned, however, in the mouth 25 of the barrier

24 through which it outwardly moves for a distance equal to the movement of contact 20 in the chamber 14 under propulsion of spring 23. To reduce the cost of manufacture, the hous- 55 ing half 12 may be constructed identically to half

12a. By providing interlocking symmetry to each side about axis A—A, the pattern is furnished for the mating of the two identical parts. Thus the post of housing half 12a, corresponding to post 28, fits into the post hole 27, to center and give lateral securement to the two halves 12 and 12a. Similarly the counterpart ridge 28a in the opposing half 12a of ridge 28 encircling one half the margin of the fuse chamber 13 is seated in groove 29 forming the remainder of the periphery.

Recesses 30 and 31 are provided in the housing for the fuse blades 17 and 18 respectively, and recesses 32 and 33 form pockets for connecting contact springs 34 and 35 which electrically connect blade 17 to the end of Nichrome wire 22 at its contact 20, and blade 18 to contact 21 respectively.

The blades may be notched at 36 to fit tongue 37 of the housing to interlock the parts, and prevent accidental movement which might affect the fuse wire 19.

In assembling the parts, the fuse chamber 13 is filled with the arc quenching and explosion suppressing material 19a, as for instance rock-wool, and the grooves 28 and 28a filled with any suitable cement which will cause the two halves to be sealed and securely cemented, when properly applied to each other. The indicator chamber 14 may be filled with a silicon heat resisting grease which will permit a seal of the parts during movement when the Nichrome wire is blown. The silicon grease may be obtained from Dow Corning Corporation under the designation DC4.

Thus when the two mating halves 12 and 12a are secured together, the limiter is sealed from the outside atmosphere, even in the indicator chamber, and will retain at all times its normal atmospheric characteristics until blown.

The limiter is externally shaped to provide finger grips 38. The limiter when blown will cause the plunger to project through one of the finger grips, interfering with its function, as is shown in Fig. 1. Thus the limiter may indicate its condition simply by placing the fingers on the grips.

Below the finger grips insulating barriers 39 of the housing extend alongside one edge of the blades to prevent accidental contact with the current during installation. The housing may be externally bridged as at 40 to accommodate the fuse chamber without weakening the wall thereof.

The plunger may be made of insulating material that can accept a fluorescent red dye to facilitate visual inspection.

Finally a plug 41 may be cemented in the mouth 25a of the counterpart half after insertion of the silicon grease into the indicator chamber 14 to seal the chamber.

In operation, the limiter is inserted into a standard base where the blades make contact with spring clips of well-known construction and not shown here. The current flows from blade to blade, through the fuse wire made of relatively low resistance material such as silver. The fusible element is designed to melt when a certain combination of current intensity and time of flow is reached in the circuit, which, if continued longer would endanger the circuit. If the path of least resistance is broken, the current will be shunted through contact springs 34 and 35 to the Nichrome wire which being of high resistance will instantly release spring 23. This action causes the projection of plunger 11 to the outside of fin-

ger grip 38 and through mouth 25, as is shown in Fig. 2.

The plunger does not interfere with removal of the limiter for it is resiliently held in position by the spring 23 which will be recompressed to permit the plunger to be pushed back in its chamber upon fingering the grips 38.

In Fig. 4, I have provided a protective sealing cover for the plunger whereby a flexible membrane 42 sealed as at 43 to the housing 44 is outwardly positioned when the plunger 45 is released by the spring not shown. The usual cement may be used to seal off the parts, allowing the flexible but non-permeable plastic membrane to be outwardly driven by the plunger to furnish the desired indication, as shown by the dot-dash lines.

In the foregoing specifications I have described an explosion-proof limiter which is not dependent upon transparent walls to permit its condition to be detected.

My limiter is exceptionally easy to assemble for the indicator forms a sub-assembly and with the blade and fuse sub-assembly enables the few parts to be quickly installed in manufacture.

The use of silicon grease enables me to seal off the moving parts when the Nichrome wire melts, thus reducing the fire hazard and maintaining the electrical characteristics of the limiter.

When a battery of my limiters are placed in stack formation, by running one's finger alongside the grips, the blown fuse may be instantly located even in a darkened fuse box.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein shown and described are only some of the many that can be employed to attain these objects and accomplish these results.

I claim:

1. In a current indicating limiter comprising a housing, a pair of connecting members having outside contacts, a fuse connected thereto, and a chamber for said fuse; an indicator chamber positioned outside of said fuse chamber, conducting means positioned outside the fuse chamber for shunting the current from the connecting members to the indicator chamber, a plunger for movement outside the limiter, means operated by said shunt current for actuating the plunger whereby an external indication will be produced when the limiter has been blown.

2. In the current limiter of claim 1, wherein the housing is provided with finger grips, and means for allowing the plunger to emerge from the housing so as to interfere with the finger grip.

3. In the current limiter of claim 1, wherein the connecting members are provided with longitudinally extending fuse blades, and the housing is provided with longitudinally extending finger grips for enabling the limiter to be handled with the fingers, said housing having insulation barriers positioned between the finger grips and the blades to prevent accidental contact therewith.

4. In the current limiter of claim 1, wherein

the housing is made of two identical parts, and contains the fuse and indicator chambers, said parts having interlocking means adapted to be cemented to each other.

5. In the current limiter of claim 1, wherein the housing contains both fuse chamber and indicator chamber each of which is provided with a seal to prevent escape of the heated contents of the chambers.

6. In the current limiter of claim 1, wherein 10 the means for actuating the plunger comprises a spring in the indicator chamber, and a wire having a higher resistance than the fuse, for releasing the spring.

7. In the current limiter of claim 5, wherein 15 the indicating chamber is provided with two openings, one for the plunger and the other for filling the chamber with a sealing material.

8. In the current limiter of claim 5, wherein the indicating chamber is sealed with a silicon grease.

9. In the current limiter of claim 6, a unitary assembly consisting of the plunger, the spring and the wire.

MICHAEL D. LAZAR.
